ART OF COMPRESSING FLUID

Sellers E. Jessup, Los Angeles, Calif.

Application June 15, 1943, Serial No. 490,841

3 Claims. (Cl. 230—20)

My invention relates to improvements in the art of compressing fluid and more particularly to that class of fluid compressors which is generally although not exclusively employed for compressing air, gas and other fluids and mixtures thereof. This application is a continuation in part of my companion application Serial Number 395,162, filed May 26, 1941, now Patent No. 2,327,269, granted August 17, 1943, and is a continuation in part of my companion application, Serial Number 474,425, filed February 2, 1943, the subject matter of the present application being directed to the toggle arrangement for operating the compressor piston and means in conjunction with the toggle for controlling the exhaust from the compressor, to best suit the operation of an internal combustion engine with which the compressor may be associated, or to best suit any other requirements for which the compressor is adapted to be used.

It is a major object of the present invention to produce any or a maximum of fluid pressure over an extended period with a minimum of power, thus tending toward greater economy and saving in expense of operation. A further object is to provide means for varying the compressed fuel mixture, whereby the heat of compression can be more effectively employed, resulting in greater economy and efficiency. A further object is to best serve the requirements of any compressed fluid medium for which the compressor is employed. Among still further objects are greater efficiency, durability and simplicity of construction. To these ends my invention comprises the features of construction and combination of parts hereinafter described and claimed.

In the drawings forming part of this specification, Fig. 1 is a vertical central section of my improved fluid compressor which is of reciprocable piston and cylinder type, the piston being shown as it approaches fully fluid compression position near the inner end of its compression stroke, the fluid pressure controlled check valve being shown in wide open position; Fig. 2 is a side elevation of a detail showing the operating handle of the toggle adjustment in position assumed by the compressor piston shown in Figs. 1 and 4; Fig. 3 is a section of a detail of the toggle adjustment as shown in Figs. 1 and 2; Fig. 4 is a schematic view showing the position assumed automatically by the controlled check valve, and by the compressor piston when the adjusting means is regulated to normally produce substantially no clearance space between the check valve and the upper end of the compressor piston, and Fig. 5 is another schematic view showing the position assumed auto-

matically by the controlled check valve and by the compressor piston when the adjusting means is regulated to produce substantially maximum clearance space between the check valve and the upper end of the compressor piston.

In the drawings, I have shown my improved compressor associated with a typical internal combustion engine but the use of the compressor is not to be restricted thereby, it being understood that it may be used for any purpose desired. However it is adapted when associated with an internal combustion engine to provide the discharge of controlled fluid exhaust into its combustion chamber with highly beneficial results. A indicates the cylinder of my improved compressor, B the piston which is reciprocable in said cylinder, C a toggle lever arrangement by which the piston is reciprocated and D a suitable drive by which the toggle levers are flexed through converting rotary motion into reciprocating motion. The coacting cylinder and piston produce a fluid compression chamber having a fluid fuel ingress port 10, through the side of the cylinder and a compressed fluid exhaust port 11 at the upper end of the cylinder leading into the combustion chamber of the engine. As shown, the fluid which is compressed is adapted to be in the form of a mixture of air and vapor or gas, which is admitted through the ingress port 10 from a suitable carburettor E, the opening and closing of the ingress port being controlled by the reciprocable movement of the piston. The ingress port is positioned so that near the inner end of the intake stroke of the piston it is fully opened and a full charge of fuel mixture is initially admitted into and maintained in the compression chamber and when the piston reverses and moves forward during its compression stroke the port 10 is closed automatically.

A typical internal combustion engine of four cycle type is shown in conjunction with the compressor, in which F is the cylinder, joined with the supporting housing 12 of the compressor and G is its reciprocable piston. The latter is driven by the usual crank shaft 13 which is coupled thereto by the connecting arm 14 and journaled in the engine housing 15. The usual air intake valve 16, exhaust valve 17 and ignition spark plug 18 are provided in the upper end of the cylinder and function in their usual and well known manner as is customary with four cycle operation.

The compressor cylinder A is extended upwardly and is of increased diameter to provide a cylindrical valve chamber 20, the latter being closed by a cover plate 21. A check valve of float piston type H is arranged coaxially with and is of greater

diameter than the diameter of the piston B in the compression chamber of the compressor and closes downwardly upon the annular downwardly tapering valve seat 22. This seat is arranged at the junction between the compression cylinder A and the cylindrical wall of the valve chamber 20 and has an annular channel 23, adjacent to and connected with the upper portion of the combustion chamber in the cylinder F of the engine by the port passage 11. The piston check valve H is thus of floating type and reciprocates freely. By constructing valve H larger in diameter than the cylinder A of the compressor, a comparatively large valve seat area is provided whereby a very slight reciprocable opening and closing movement is necessary for discharging the compressed fluid through the restricted port passage 11 and closing of the valve. In practice a compressor employing a fluid compressing cylinder six inches in diameter has required less than one thirty second of an inch opening movement.

The valve chamber 24 containing the return check valve H is connected with the forward end of the combustion chamber of engine cylinder F by a duct 25, which latter is controlled by the ball check valve 26 and admits fluid while under sufficient compression in the combustion chamber of the engine into the valve chamber 24 above the check valve H, thus urging and maintaining the check valve H closed during the return intake stroke of the compression piston B. Closing movement of the check valve H is also augmented by the negative force of suction caused by the compression piston so that a quick and dependable closing function of said valve prevails. The compressed fluid admitted automatically into the valve chamber 24 from cylinder F also acts as a cushioning medium for valve H, during its opening movement.

The force of compression of fluid back of valve H tends to hold the valve closed during the compression stroke of the piston B until sufficient force of compression by piston B overcomes such opposed force, whereupon valve H opens and admits the compressed charge into the combustion chamber of the engine. The pressure of fluid maintained in the valve chamber 24 against the check valve H thus serves to assist in automatically controlling the exhaust or egress of compressed fluid from the compression chamber of the compressor into the combustion chamber of the engine as will be hereinafter described.

The piston B of the compressor is reciprocated in the cylinder A through the medium of toggle C, which together with the crank shaft 13 are contained in the supporting housing 12, said housing being part of the compressor cylinder structure. The toggle C consists of a pair of lower fulcrum and upper toggle arms 30 and 31, which are flexed and expanded and pivotally connected between their inner ends and to the outer end of the drive connecting rod 32 by the pintle 33. The outer end of the toggle arm 31 is pivotally connected with piston B by the pivot pin 34 while the outer end of the toggle arm 30 is adjustably fulcrumed upon the supporting housing 12 through the medium of a cam 35, which is journaled by the cam shaft 36 in any suitable journal support such as provided by the opposite side walls of the housing 12. The forward end of the cam shaft projects beyond the housing and has attached thereto a laterally extending lever arm 37 by which the cam can be manually rotated to regulate the length of stroke of the pair of toggle arms. The adjustment of

the clearance space thus provided by the piston B in cylinder A below valve H in cooperation with said valve assists in regulating and controlling the pressure of fluid medium discharged into the combustion chamber of the engine. The manually operable lever 37 swings over the lock ring 38, which is concentric with the axis of the cam shaft 36 and fixed on the side of the housing. Said operating lever can be locked in any selected adjustable position by the removable lock pin 44, which is insertable in any one of the suitably spaced holes 39 in the lock ring. When it is desired to regulate the stroke of the compression piston B to control the exhaust of compressed fluid medium through toggle levers D, the same may be accomplished by swinging the operating lever 37 and rotating the cam 35. Thus the toggle is adjusted longitudinally of the cylinder A without changing the initial volume of fluid which is admitted into the combustion chamber F, and whereby the compression of the charge of fluid is regulated and varied in the compression chamber to suit requirements so that the force of combustion is applied most advantageously at the initial starting of the power stroke of the engine and continuing thereafter for a considerable period. In this manner highly efficient results and a maximum of power are produced from a minimum quantity of fuel. This adjustment provides means for regulating the clearance space below compression check valve H and the admission of a fixed constant volume of fuel mixture which is admitted into the combustion chamber to produce any ultimate compression of the mixture charge desired, or if desired the entire admission of fuel mixture may be checked to enable the engine to idle. In the latter operation the check valve H closes the admission orifice automatically.

In Figure 4 the compressor piston B and toggle C are shown adjusted in maximum upper position when no clearance space is provided and the admission valve H is open as during the intake stroke of the engine piston G. In Fig. 5 the compressor piston B and toggle C are shown adjusted in lowermost position when maximum clearance space is provided and the admission duct 11 is closed automatically by the admission valve B during the compression stroke of the engine piston G. Any intermediate adjustment to vary the compression may be provided. It will be noted that the toggle also performs the function of prolonging the compression and delivery of fuel mixture and while the port 11 is sufficiently restricted to cooperate and assist in regulating the feed of the compressed fuel mixture it may not be restricted when desired and the prolonged functioning of the discharge accomplished.

The toggle C is shown driven through the connecting rod 32 by the crank shaft 40, which is journaled in the housing 12 and in turn driven by the driven sprocket 41, chain belt 42 and drive sprocket 43, the latter being driven by the crank shaft 13 of the engine. The relative diameter of the two sprockets 41 and 43 is such that the compressor piston B is reciprocated in synchronism with the speed of the engine, that is at suitable speed which is correlated with the stroke of the engine of that type with which the compressor is employed, the engine illustrated being a four cycle type and the ratio of speed being one revolution of the compressor crank shaft 40 to two revolutions of the engine

shaft 13. It will be understood that any suitable drive may be employed.

The application of the toggle is such that the highest and predominating degree of compression of the fuel mixture occurs when the engine piston starts on its power stroke. This predominating compression of fuel mixture delivered by the compressor into the engine cylinder continues over an unusually prolonged period while the engine piston advances on its power stroke due to the pause in movement of the toggle and partly by the constricted exhaust port 11.

The general operation of the engine and cooperating compressor is substantially similar to that described in my copending applications above referred to, the toggle functioning to deliver over a prolonged period due to a comparatively slow turn over from dead end position toward flexed position of the toggle, the first portion of which is comparatively slow and prolonged resembling a pause as compared with the latter portion. During the first portion of the compression stroke of the toggle referred to, the power piston of the engine quickly completes its power stroke. In this manner a continuous supply of compressed fuel is delivered during the pause in the movement of the compressor piston and admixed with a charge of air previously compressed in the combustion chamber of the engine as the piston thereof advances during its power stroke. When desired the stroke of the compressor piston B can be regulated by adjusting the manually operable lever 37. In this manner the compression by the toggle driven piston B, in coordination with the automatically compressed check valve H controls the exhaust of compressed fuel medium discharged into the combustion chamber of the engine so that the force of combustion is applied most advantageously at the initial starting of the power stroke and continuing thereafter for a considerable period. In this manner highly efficient results and a maximum amount of power are produced from a minimum quantity of fuel. The adjusting feature thus provides means for initially admitting an even volume of fuel mixture into the combustion chamber while the variable stroke of the compression piston B varies the compression of the charge of mixture charge, or if desired the entire admission of fuel mixture may be checked to enable the engine to idle. In the latter operation the check valve H closes the admission orifice 11 automatically. The heat of compression in the compressor cylinder allows the use of any suitable hydrocarbon fuel mixture in the engine.

It is contemplated that the compression of the check valve H may be accomplished by other means than provided automatically by the valved connection 25, Figs. 4 and 5 illustrating a manually controlled valved compressed fluid supply duct 45 by which air or other fluid under sufficient pressure can be maintained in the valve chamber 24 to cause the check valve to function

in cooperation with the toggle adjustment for controlling the exhaust of fluid discharged into the combustion chamber of the engine.

While I have shown and described the application of my improved toggle actuated compressor in conjunction with an internal combustion engine of four cycle type it will be understood that my improvement is applicable to other types of engines or for compressing fluid for other purposes without departing from the spirit of the invention and within the scope of the following claims.

I claim:

1. In a compressor having a cylinder provided with ingress and exhaust ports, a support for said cylinder, a reciprocable piston coacting with said ingress and exhaust ports to form a compression chamber of initial constant volume in said cylinder, a pair of toggle levers having one end portion pivotally connected to said piston, a variable bearing for the opposite end of said toggle levers on said support whereby a variable clearance space is provided by said piston in the compression chamber to assist in regulating the compression of fluid by said piston, said adjustable bearing being manually operable to regulate said compression without changing the size of said admission port, and means for flexing the toggle levers to reciprocate said piston.
2. A compressor, comprising, a cylinder provided with admission and exhaust ports and a support, a reciprocable piston coacting with said admission and exhaust ports to form a compression chamber of initial constant volume in said cylinder, a pair of toggle levers having one end portion pivotally connected with said piston, a variable bearing for the opposite end of said toggle levers on said support whereby a variable clearance space is provided by said piston in the compression chamber to assist in regulating the compression of fluid by said piston, said adjustable bearing having operating means to regulate said compression without changing the effect of the admission port, and means for flexing the toggle levers to reciprocate said piston.
3. A compressor, comprising, a cylinder provided with fluid admission and exhaust ports and a support, a reciprocable piston coacting with said admission and exhaust ports to form a compression chamber in said cylinder, a pair of toggle levers flexed together and having one end portion pivotally connected with said piston, a variable bearing for the opposite end portion of said toggle levers on said support, means for regulating said variable bearing whereby a variable clearance space is provided by said piston in said compression chamber to regulate the effective compression of fluid by said piston, means for operating said adjustable bearing to regulate said effective compression without changing the effect of said admission port, and means for operating the toggle levers, whereby said piston is reciprocated and its effective compression stroke period is increased or decreased.

SELLERS E. JESSUP.
